UNITED STATES PATENT OFFICE

HENRY WEIGAND, OF WILKES-BARRE, AND OSCAR E. SCHOBERT, OF PITTSTON, PENNSYLVANIA, ASSIGNORS TO PENN TOBACCO COMPANY, OF WILKES-BARRE, PENNSYLVANIA, A CORPORATION OF PENNSYLVANIA

TOBACCO-STEMMING MACHINE

Application filed June 22, 1927. Serial No. 200,679.

The invention relates to machines for removing the stems from tobacco leaves, of the general type embodying a traveling member having leaf stripping means, and stem-pulling means for engaging the leaf stems at their butt ends and pulling said stems through the leaf stripping means. Machines of this character have been heretofore successfully used but the stem-pulling means thereof have usually gripped portions of the leaf body along the butt ends of the stems, tearing such portions from the remainder of the leaf bodies and hence causing waste. It is one object of the present invention however, to provide an improved stemming machine, in which the portions of the leaf bodies along the butt ends of the stems, are removed by novel means prior to engagement of said butt ends with the stem-pulling means. Thus, not only may a saving be effected, but the stem butts are exposed and hence prepared for easy positioning in the leaf stripping knives or the like.

The stem-pulling means commonly employed bodies driven yieldably mounted rollers for gripping the stems and pulling them through the stripping means. These rollers are parallel with the line on which the leaves are fed by the machine and they are provided with tapered ends to facilitate engagement of the stems therewith. The stem butts however often do not enter between the rollers and hence trouble is caused and numerous un-stemmed leaves must be thrown aside for repassage through the machine or to be stemmed in some other way. A further object is to provide novel means to facilitate initial engagement of the stem butts with the stem pulling means, thereby overcoming such difficulties as those above stated.

Stemming machines of the type set forth embody a cutter for severing the stems near their inner ends, while said stems are being moved transversely of their own lengths by the stripping means and in the direction of said lengths by the stem pulling means. These cutters are the source of quite an amount of trouble and it is another of our objects to provide an improved cutter and one which is adjustably mounted in a unique

manner to permit severing of the stems at the desired points.

While the stems are being pulled through the stripping means, they are commonly held in engagement with said stripping means by a vertically movable plate. The wear against the lower edge of this plate has been so as to make it short-lived, but we aim to make novel provision whereby such wear will not affect the plate but will be received by an edge of an auxiliary plate, the latter being so mounted that when one edge becomes badly worn, another edge may be presented for use, and when both edges are badly worn, another auxiliary plate may be substituted.

A still further aim is to provide a stemming machine which will be rather simple and inexpensive, easy and economical to operate, and unusually efficient.

With the foregoing and minor objects in view, the invention resides in the novel subject matter hereinafter described and claimed, the description being supplemented by the accompanying drawings.

Fig. 1 is a top plan view of a tobacco stemming machine constructed in accordance with our invention.

Fig. 2 is a front elevation.

Fig. 3 is a rear elevation.

Fig. 4 is a longitudinal sectional view on line 4—4 of Fig. 1.

Fig. 5 is a vertical transverse section substantially on line 5—5 of Figs. 1, 2 and 3.

Fig. 6 is an enlarged rear elevation partly broken away and in section, showing the means for removing the portions of the leaf bodies along the butt ends of their stems.

Fig. 7 is a horizontal sectional view substantially on line 7—7 of Fig. 6.

Figs. 8 and 9 are vertical transverse sections substantially on lines 8—8 and 9—9 of Figs. 6 and 7.

Figs. 10 and 11 are respectively a side elevation and an edge view of one of the beater arms which are instrumental in cleaning portions of the leaf bodies from the stem butts.

Fig. 12 is a transverse section on line 12—12 of Fig. 10.

Fig. 13 is an enlarged rear elevation partly

in section, of the stem pulling means, and the associated stem cutting means.

Fig. 14 is a horizontal section on line 14—14 of Fig. 13.

5 Fig. 15 is a transverse sectional view on line 15—15 of Figs. 13 and 14.

Fig. 16 is a view similar to Fig. 15 but showing a stem butt engaged with the pulling means.

10 Figs. 17 and 18 are respectively a side elevation and an upper edge view of the main and auxiliary plates which hold the stems in engagement with the leaf stripping means.

Fig. 19 is a perspective view of the stem-cutting disk and its adjustable supporting means.

Fig. 20 is a perspective view of the spring device for forcing the stems into engagement with the cutting knives.

20 Figs. 21 and 22 are perspective views of opposite sides of portions of the chain belt carrying the stripping knives.

A frame is shown embodying two longitudinal bars 20, legs 21, braces 22 and one or 25 more transverse members such as 23, secured to the bars 20. Mounted longitudinally upon the frame, is a table 24 defining a path along which the leaves are fed transversely of their own lengths, with their butt ends disposed in 30 one direction, a suitable gauge wall 25 being provided to assist in initially positioning these butt ends upon the table, as will be clear from the left hand end of Fig. 1.

An endless feed apron 26 is provided having 35 its upper reach disposed on an upper front portion of the table 24, said apron being trained around a driven roller 27 near the center of the machine and an idle roller 28 near the inlet end of said machine. The

40 bearings 29 for the roller 28 are provided with suitable adjusting means 30 whereby slack may be taken out of the apron when desired. The roller 27 is secured to a shaft 31 mounted in appropriate bearings 32 and 33, bearing 32 being secured to the foremost of 45 the bars 20, while bearing 33 is secured to one of a pair of upstanding standards 34 which have their lower ends attached to the rear-most bar 20, in any desired manner. Ap-

50 propriately mounted on the other of these standards 34, is a sprocket 35 disposed at the rear edge of the apron 26, and a larger sprocket 36 of greater diameter than the roller 27, is secured upon the shaft 31 at the 55 rear end of said roller 27. Trained around the two sprockets 35—36 and disposed at the rear edge of the apron 26, is a chain belt 37.

Another chain belt 38 is positioned over the belt 37 and is driven at the same speed as the 60 latter. Sprockets 39 and 39^a are provided for the belt 38, said sprockets being secured to short shafts 40—41 rotatably mounted in appropriate bearings 42—43, secured to the standards 34. The shaft 41 of the sprocket

65 39^a is adjustably mounted as at 44 so that

slack may be removed from the belt 38, and similarly, a member 35^a which is instrumental in mounting the sprocket 35 upon one of the standards 34, is adjustably connected with this standard as at 44^a, permitting the removal of slack from the lower belt 37. The shaft 40 is positioned above the shaft 31 and the two shafts are connected by gearing 45 so that the contiguous reaches of the belts 37—38, travel at uniform speed. This speed however is greater than the speed at which the belt 26 travels, due to the fact that the sprocket 36 is of greater diameter than the roller 27, said sprocket controlling the driving of both belts 37—38 whereas said roller drives the apron 26. This difference in speed between that of the apron 26 and that of the belts 37—38, is instrumental in positioning the tobacco leaves obliquely of the table as shown in dotted lines in Fig. 1, for a purpose to be hereinafter described.

The shaft 31 may be driven in any desired manner. We have shown a sprocket 46 on the front end of this shaft engaged with a chain 47, said chain being trained around one of a pair of sprockets 48, the other of which is driven by a chain 49 and a sprocket 50 from a transverse shaft 51 mounted in appropriate bearings at the outlet end of the machine, a belt 52 and pulley 53 being shown for driving said shaft 51.

The adjacent reaches of the chains 37—38, grip the butt ends of the leaves while the latter rest upon the apron 26, assist in conveying said leaves along the table 24, co-operate with said apron 26 in angling the leaves as above explained, and serve to tightly hold the leaves while portions of the leaf bodies along the butt ends of the stems are being removed.

To remove these leaf portions, we provide a rotatable beater 54 mounted on a shaft 55 which is disposed at the rear side of the machine, in rearwardly spaced relation with the aforesaid belts 37—38. The butt ends of the leaves project rearwardly from these chains as shown in Fig. 9 and also in Fig. 1, and these projecting butt ends are acted upon by the beater arms 56 of the beater 54, so that the body portions of the leaves along the butt ends of the stems, are effectively re-

60 moved by said beater arms, the removed leaf portions being discharged through an appropriate chute 57, at the lower end of which they may be sacked or received in any desired receptacles.

To hold it against depression, the upper reach of the chain 37 travels in a channeled track 58 secured to the table 24, and to depress the lower reach of the chain 38 into effective co-operative relation with said upper reach of said chain 37, we provide a channeled shoe 59 engaging said reach of chain 38, this shoe being shown in Figs. 2, 4, 6, 7, 8 and 9. This shoe is secured by bolts or the like 60 to the front ends of spring arms 61, spacing 65

70

120

125

130

blocks 62 being preferably interposed between said shoe and arms. The rear ends of the arms 61 are secured for vertical adjustment as at 63, to a pair of plates 64 whose upper ends are bolted or otherwise secured to a longitudinal bar 65 whose ends are anchored to the standards 34. The spring arms 61 are disposed at opposite ends of the beater 54 and positioned over this beater, is a yieldable 10 concave 66, one longitudinal edge of this concave being secured to the shoe 59 by bolts or the like 67, while its opposite edge is bolted at 68, for vertical adjustment, to a block 69^a, said block being secured at 69^b to the bar 65 between the plates 64. The adjustments 68 permit lowering of the concave 66 as the beater arms 56 wear off at their ends and also allow raising of said concave when new beater arms are installed. The adjustments 63 15 above described in connection with the spring arms 61, permit necessary adjustment to obtain the desired tension on said arms. Preferably, these arms carry a pair of end walls 69 for the concave 66.

25 The beater shaft 55 may be driven in any desired manner, for instance, by a belt 70 and pulleys 71, from a longitudinal shaft 72 mounted at the rear side of the machine. Shaft 72 may be driven by a belt 73 and pulleys 74 from a longitudinal drive shaft 75 disposed at the rear side of the machine, at the discharge end of the latter, appropriate means such as a belt 76 and tight and loose pulleys 77, being employed for driving said 30 shaft 75.

An endless chain belt 78 is disposed in overlapping relation with the apron 26 and the lower feed belt 37 and is guided by an appropriate hollow track 79 secured to the 35 table 24, said belt 78 being trained around a sprocket wheel 80 loose upon the shaft 31 and around another sprocket 81 which is secured to the transverse shaft 51. This belt 78 is positioned at the rear portion of the 40 table 24, at the delivery end of the latter and said belt carries leaf stripping means in the form of knives 82. Each knife is provided with a notch 83 of a size to receive a leaf stem, and adjacent edges of said knives 45 are cut to jointly form additional notches 84 of substantially the same size as the notches 83. The butt ends of the stems, after they have been cleaned by the beater 54, are positioned in the notches 83—84 and by the latter are carried on toward the delivery end of the machine, during which movement, the butt ends of the leaf stems are engaged with stem-pulling means, hereinafter described. As the leaves are released from the chains 50 37—38, they enter the notches 83—84 and to hold them in these notches when initially positioned therein, spring arms such as 85 may be employed.

Relatively yieldable upper and lower, stem-pulling rollers 86—87 are mounted behind

the belt 78 and parallel therewith, roller 87 being secured to the shaft 75, while roller 86 is geared at 88 to said shaft 75. The bearings for these two rollers are carried by appropriate standards 89 secured to the rear-most of the bars 20, the bearings for the upper roller 86 are mounted for vertical yielding, and adjustable springs 90 are employed for yieldably depressing said bearings so as to hold the rollers 86 and 87 in cooperative relation with each other. These rollers are beveled at one end as indicated at 91, to facilitate reception of the stem butts between them, said butts projecting rearwardly from the stripping means 82, as shown in Fig. 1. At this time, that is when the stem butts engage the rollers 86—87, the leaves are obliquely positioned as shown in Fig. 1, and such oblique positioning gives the rollers a much better chance to rapidly grip the stem butts and pull the stems from the body portions of the leaves, while the latter are held in check by the knives 82. To facilitate guiding of the stem butts into the space between the tapered roller ends 91, 90 suitable guides such as 92 (Fig. 13) may be employed.

To hold the stems down in the notches 83—84, while said stems are being stripped from the leaves by the rollers 86—87, we provide a heavy plate 93 connected with the front edges of the standards 89, as at 93^a, these connections being such as to permit vertical floating of said plate 93 according to the varying diameters of the leaf stems. The stems are pulled under the lower edge of the plate 93 and to protect said edge against wear, we secure an auxiliary plate 94 to one side of the plate 93 by screws 95. This auxiliary plate is provided with two straight longitudinal edges 96, either one of which may be downwardly positioned to engage the stems. Hence, when one edge 96 has become badly worn, the plate may be inverted and the other edge positioned for use. Then, too, when both edges are seriously worn, the entire plate 94 may be replaced with a new one. The greater part of wear on the auxiliary plate 94 is toward its front end and when such end has become 100 badly worn, the rear end of the plate is still 105 usable. Hence, this plate may also be turned end for end to obtain additional wear.

Positioned between the stem-pulling means 86—87 and the stripping means 82, is a stem cutting disk 97 of circular form, the lower edge of this disk being in close proximity with the upper side of the track 79 so that said side is tangential to the peripheral edge of the disk. As the leaves are being fed toward the delivery end of the machine and as the stems are being pulled from the leaf bodies by the rollers 86—87, said stems must pass between the peripheral edge of the disk 97 and the top of the track 79 tangential 110 115 120 125 130

thereto with the result that said stems will be severed, leaving their delicate tips in the body portions of the leaves. Provision is made, whereby this disk 97 may be adjusted 5 to different positions, to sever the stems sooner or later, as occasion may demand. In the preferred form of construction, the disk is rotatably mounted on a stub 98 secured to an arm 99, said arm being secured to and 10 projecting downwardly from a longitudinal bar 100, which bar is connected at 101 with the upper ends of the standards 89, in such manner that this bar may be longitudinally moved to any desired position and then held 15 in such position, thus disposing the cutting disk 97 at the most advantageous location. When this disk is positioned toward the inlet end of the machine, the stems will be severed more quickly, that is further from 20 the tips of the leaves than if said disk be set at a position toward the delivery end of the machine. Whenever the stock runs rather poor and short for a period of time, the cutter disk may be adjusted toward the inlet 25 end of the machine to sever the stems at the proper points and when longer stock is encountered, the cutter may be rearwardly adjusted to the required extent.

The stems, pulled out by the rollers 86—87, 30 discharge through an appropriate chute 102 and the leaf bodies are carried onto the delivery end of the table 24 by the stripping means 82. At this point, appropriate cam means 103 disengages the leaf bodies from 35 the stripping means and said bodies then slide down an appropriate chute 104.

In operating the machine, the leaves are placed transversely upon the table 24 and belt 26 as shown in Fig. 1, with their butt 40 ends engaging the wall 25. The apron 26 feeds the leaves until they are gripped between the chains 37—38, and the feeding operation then continues, with the butt ends 45 of the leaves projecting from said chains. The rotary beater 54 is in the path of these projecting butt ends, with the result that its beater arms 56 remove the portions of 50 the leaf bodies along the butt ends of the stems, said removed leaf portions being discharged through the chute 57. When the stem butts are released by the chains or belts 37—38, they are directly over the knives 82 of the upper reach of the belt 78, to be carried by these knives under the plate 93. 55 When this plate is reached, due to the relative speeds of the belts 37—38 and the apron 26, the leaves have been obliquely positioned as shown in dotted lines in Fig. 1, with the result that as said leaves are further fed 60 along the table 24 by the stripping means 82, their butt ends are directed toward the rollers 86—87. Hence, the tapered ends 91 of these rollers may more readily grasp the butt ends of the stems than would otherwise 65 be possible. As soon as these rollers grip

the stems, they pull the latter through the stripping means 82 and during this pulling operation, said stripping means continues to feed the leaves toward the delivery end of the machine. Thus, by the time the major 70 portions of the stems have been pulled from the leaf bodies, the stems contact with the cutting disk 97 and are severed, leaving the delicate stem tips in the leaf bodies. The stems discharge through the chute provided 75 for that purpose, the stripped leaves continue toward the discharge end of the machine, with the stripping means 82, the cam means 103 then frees said stripped leaves 80 from said stripping means, and said leaves finally slide down the chute 104.

To secure the beater arms 56 to the body or hub 105 of the beater 54, we mount the inner ends of these arms in openings 106 in bars 107 (Figs. 6 and 9) preferably formed of 85 wood, and secure these bars by bolts 108 to flanges 109 on said body or hub 105. The inner extremities of the arms 56 are turned laterally as shown at 110 (Figs. 10, 11 and 12), these laterally turned ends lie within 90 grooves 9 (Fig. 6) in the inner edges of the bars 107, and detachable metal strips 111 are secured to said inner edges of the bars 107, to hold the arms in place prior to securing the bars 107 to the flanges 109. Each 95 arm is preferably of square cross-section as shown in Fig. 12 and its lateral end 110 holds it against turning so that one of its sharp corners will be presented to the work.

As the outer ends of the arms 56 wear 100 away, the bars 107 may be adjusted outwardly, for which purpose the bolts 108 pass through slots 112 in the flanges 109. Preferably, the arms 56 of any row are staggered 105 with respect to those of the next adjacent row, insuring that anything missed by the arms of one row will be caught by those of the next.

It will of course be understood that suitable guards and hoods may be provided 110 wherever necessary to protect the operators from moving parts, but such guards or hoods have been omitted from the present disclosure in order to fully illustrate parts which would otherwise be more or less obscured. 115

We claim:

1. In a tobacco stemming machine, a traveling member having leaf stripping means to engage the butt ends of leaf stems, stem pulling means at one side of said member for pulling the stems through the stripping means as said stems are moved by said stripping means, a rotatable stem cutting disk between said stripping means and said pulling means and rotated by contact with the stems as the latter are moved by said stripping means and are pulled by said pulling means, and a stationary surface tangential to the peripheral edge of said disk, the stems 120

being forced between said edge and said surface by said stripping means.

2. In a tobacco stemming machine, a traveling member having leaf stripping means to engage the butt ends of leaf stems, stem pulling means at one side of said member for pulling the stems through the stripping means as said stems are moved by said stripping means, a rotatable stem cutting disk between said stripping means and said pulling means, the inner ends of the stems being forced against said disk by said stripping means, and means mounting said disk for adjustment along the line of travel of said traveling member.

3. In a tobacco stemming machine, a traveling member having leaf stripping means to engage the butt ends of leaf stems, stem pulling means at one side of said member for pulling the stems through the stripping means as said stems are moved by said stripping means, a bar disposed longitudinally of and above the line of travel of said traveling member, means mounting said bar for adjustment longitudinally, and a stem cutter mounted on said bar and disposed between said stripping means and said pulling means for contact with the inner ends of the stems as the latter are moved by said stripping means and are pulled by said pulling means.

4. In a tobacco stemming machine, a traveling member having leaf stripping means to engage the butt ends of leaf stems, stem pulling means at one side of said member for pulling the stems through the stripping means as said stems are moved by said stripping means, a rotatable stem cutting disk between said stripping means and said pulling means for engagement with the inner ends of the stems while the latter are moved by said stripping means and are pulled by said pulling means, and means mounting said disk for adjustment longitudinally of the line of travel of said traveling member, said mounting means embodying an arm carrying said disk, a bar disposed longitudinally above said stripping means and carrying said arm, and means securing said bar.

5. In a machine of the class described, means for gripping leaves near their butt ends and conveying said leaves with said butt ends projecting laterally in one direction, said gripping and feeding means embodying a belt to lie upon the leaves and a shoe for holding said belt down, a rotary beater in the path of said lateral ends having a shaft parallel with said gripping and conveying means, a yieldable concave above said beater connected at one edge to the aforesaid shoe, stationary supporting means to which the opposite edge of said concave is secured, and spring arms secured to said supporting means and carrying said shoe.

6. A structure as specified in claim 5; to-

gether with end walls for the concave secured to said spring arms.

7. In a tobacco stemming machine, a horizontal roller having a drive shaft, a feed apron upon which to lay tobacco leaves with their butt ends projecting beyond one edge of said apron, said apron being trained around said roller, two sprockets secured on said shaft at the end of said roller adjacent said one edge of the apron, upper and lower gripping belts at said one edge of said apron for gripping the leaves near their butt ends, means for stripping the leaf portions from the butt ends of the leaves while held by said gripping belts, the lowermost of said belts being trained around and driven by one of said sprockets, another belt trained around the other of said sprockets and having stripping means to which the cleaned butt ends of the leaf stems are presented by said apron and said gripping belts, and stem-pulling means with which the ends of the leaf stems are engaged by said stripping means.

8. In a tobacco stemming machine, a horizontal roller having a drive shaft, a feed apron upon which to lay tobacco leaves with their butt ends projecting beyond one edge of said apron, said apron being trained around said roller, two sprockets secured on said shaft at the end of said roller adjacent said one edge of the belt, the innermost of said sprockets being of larger diameter than said roller, a butt-engaging feed belt having a horizontal reach parallel with and disposed at said one edge of said apron, said belt being trained around said large sprocket wheel and hence traveling at a greater speed than said apron to dispose the leaves obliquely of the apron with their butt ends leading, another belt trained around the outermost of said sprocket wheels and having leaf-stripping means into which the stem butts are delivered by said apron and the first named belt, and upper and lower pull rollers having tapered ends between which the stem butts are directed by said stripping means.

In testimony whereof we have hereunto affixed our signatures.

HENRY WEIGAND.
OSCAR E. SCHOBERT.
